UNITED STATES PATENT OFFICE

168,008

BASEBOARD RADIATOR ENCLOSURE

Henry S. Woodruff, Newark, N. J., assignor to The Variflame Corporation, White Plains, N. Y., a corporation of New York

Application October 17, 1951, Serial No. 16,971

Term of patent 14 years

(Cl. D81—21)

To all whom it may concern:

Be it known that I, Henry S. Woodruff, a citizen of the United States, residing at Newark, county of Essex, and State of New Jersey, have invented a new, original, and ornamental Design for a Baseboard Radiator Enclosure, of which the following is a specification, reference being had to the accompanying drawing, forming part thereof.

The figure is a perspective view of a baseboard radiator enclosure showing my new design. The broken lines are for illustrative purposes.

I claim:

The ornamental design for a baseboard radiator enclosure, substantially as shown and described.

HENRY S. WOODRUFF.
